UNITED STATES PATENT OFFICE

90,768

DESIGN FOR A DECORATED DISK

Frank C. Hutchison, Kansas City, Mo.

Application July 17, 1933. Serial No. 48,741

Term of patent 7 years

To all whom it may concern:

Be it known that I, FRANK C. HUTCHISON, a citizen of the United States, residing at Kansas City, in the county of Jackson and State of Missouri, have invented a new, original, and ornamental Design for a Decorated Disk, of which the following is a specification, reference being had to the accompanying drawing, forming a part thereof.

Fig. 2 is a cross sectional view taken on line II—II of Figure 1.

I claim:

The ornamental design for a decorated disk, as shown.

FRANK C. HUTCHISON.
